UNITED STATES PATENT OFFICE.

CLAUDE WHITTET, OF HAVANA, ILLINOIS.

DRILLING MACHINE.

Application filed September 28, 1927. Serial No. 222,437.

This invention relates to new and useful improvements in drilling machines and more especially to what is known as the walking beam.

5 The device consists in the novel features of construction, combination and arrangement of parts illustrated in the accompanying drawings and more particularly pointed out in the appended claims.

10 In the accompanying drawings, which are for illustrative purposes only and are therefore not drawn to scale:

15 Figure 1 is a side elevation, illustrating the position of the walking beam and flexible tensioning device for the drilling cable.

Figure 2 is a similar view, with the walking beam and associated parts in drilling position.

20 Figure 3 is a horizontal section, taken on line 3—3 of Figure 1 and Figure 4 is a vertical transverse section, taken on line 4—4 of Figure 2, looking in the direction indicated by the arrows.

25 Referring to the drawings for a more particular description of my invention and in which drawings like parts are designated by like reference characters throughout the several views, my device comprises the Samson post A, consisting of the laterally spaced parallel uprights 1, which provide a support for the walking beam 2, and between the upper ends of which uprights, the walking beam is pivoted by the cross pins or bolts 3. The walking beam 2 is composed of two corresponding parallel bars or members 4 held in spaced relation by the end spacing blocks 5 and joined together at corresponding ends by the transverse bolts 6, which also extend through the spacing blocks aforesaid.

30 A flexible tensioning device B for the drilling cable 6, is used in carrying out my invention, and comprises the corresponding parallel shorter bars 7, pivoted at their inner ends, as at 8, to the upper ends of the two members of the Samson post A and a longer bar or link 9. The bar or link 9 is pivotally connected at its inner end, as at 10, between the outer ends of the bars 7 of the tensioning device and is provided at its outer end with the pulley 11. When the parts are in the position illustrated in Figure 1, as in hoisting and lowering the drilling tools, the bars 7 of the flexible tensioning device are in a substantially horizontal position and the longer bar or link 9 of the latter disposed at an up-

ward inclination of approximately 45 degrees. Under these conditions, the pulley 11 is disposed above but adjacent the pulley 12, journaled between the bars or members 4 of the walking beam and the drilling cable passes 60 down in a direct or straight line between said pulleys.

In drilling, the link 9 of the flexible tensioning device is swung inwardly together with the pulley 11, into a vertical position, 65 as shown in Figure 2 and held in such position by the keeper pin 13, which is inserted through the aforesaid pulley and the openings 14 in the upper ends of the upright members of the Samson post. My construction and 70 arrangement of the pulleys 11 and 12, is such as to eliminate friction on the drilling cable while the drilling tools are in operation.

75 It will be understood that the drilling cable has one end fastened on the hoisting drum of the drilling rig and carries the drilling tools at its opposite or free end. The numeral 15 indicates the rig derrick and 16 the frame of the drilling rig.

80 From the foregoing description taken in connection with the drawings, it is thought that the construction, operation and advantages of my invention will be readily understood without requiring a more extended explanation.

85 Various changes in the form, proportions and minor details of construction may be resorted to without departing from the principles or sacrificing any of the advantages of my invention as defined in the appended claims.

90 Having described my invention, what I claim as new and desire to secure by Letters Patent, is:

1. In a device of the character specified, a Samson post, a horizontal walking beam, 95 pivotally mounted thereon, a pulley journaled to the outer end of the walking beam, a flexible tensioning device for the drilling cable, said device comprising shorter inner bars and an outer longer bar provided at its free end 100 with a pulley, the outer longer bar and said last mentioned pulley adapted to extend at an upward inclination or moved inwardly into vertical position and means for holding said outer longer bar and pulley in vertical 105 position.

2. In a device of the character specified, a Samson post, a horizontal walking beam, pivotally mounted thereon, a pulley journaled to one end of the walking beam, a flexible 110

tensioning device for the drilling cable, said device comprising shorter inner bars pivoted to the Samson post and an outer longer bar pivoted to the shorter inner bars and provided at its free end with a pulley, the outer longer bar and said pulley adapted to extend upwardly at an inclination of approximately 45

degrees or moved inwardly into vertical position and a pin adapted to be inserted through the Samson post, pulley and outer longer bar for holding the latter in vertical position.

In testimony whereof he affixes his signature.

CLAUDE WHITTET.
